[57] CLAIM

The ornamental design for a simulative toy pencil sharpener, as shown and described.

DESCRIPTION

FIG. 1 is a front elevational view of a simulative toy pencil sharpener showing our new design;
FIG. 2 is a right side elevational view thereof;
FIG. 3 is a top plan view thereof;
FIG. 4 is a bottom plan view thereof;
FIG. 5 is a perspective view thereof with the front cover lifted; and
FIG. 6 is a perspective view thereof with the rear cover lifted.

FIG. 1

FIG. 2

FIG. 3

FIG. 4

FIG. 5

FIG. 6
